UNITED STATES PATENT OFFICE.

JOHN W. LEWIS AND NEWTON J. LEWIS, OF MCKAY STATION, OHIO.

WIRE-MANIPULATING TOOL.

SPECIFICATION forming part of Letters Patent No. 357,613, dated February 15, 1887.

Application filed October 7, 1886. Serial No. 215,553. (No model.)

To all whom it may concern:

Be it known that we, JOHN W. LEWIS and NEWTON J. LEWIS, citizens of the United States, residing at McKay Station, in the county 5 of Clinton and State of Ohio, have invented certain new and useful Improvements in Wire-Manipulating Tools, of which the following is a specification, reference being had therein to the accompanying drawings.

- 10 This invention relates to improvements in manipulating-tools used, principally, in twisting together the meeting ends of the strands of wire fences and telegraph and telephone wires; and the tool consists of two members, a holder 15 and a twister, the holder being composed of two hinged arms adapted to be pressed toward each other, and having recesses which, respectively, hold two pieces of wire when laid side by side, and which hold one coil of wire while 20 the other coil of the joint is being made, and the twister being composed of a single bar having a peculiarly - shaped recess in the end thereof, whereby when two wires are laid across each other each is held, and one is moved 25 around the other by simply revolving the bar about one of the said wires as a center.

In the accompanying drawings, forming a part of this specification, and on which like reference-letters indicate the same or corresponding features, Figure 1 represents a side elevation of the twister with the wires in place; Fig. 2, a like view of the holder without the wires; Fig. 3, a similar view to Fig. 1, showing the head of the twister with the wires removed; Fig. 4, edge views of the holder and twister, showing the same applied to the adjoining ends of two fence-wires; and Fig. 5, a view of said wires, showing their relative position when the tool is applied.

- 30 We will first describe the holder as it is first applied to the wires in effecting their union.

The letter A designates metallic bars fashioned after the shape shown in Fig. 1 and pivotally connected together at B by means of any 45 suitable hinge-joint. These bars are recessed at C, to form in each two semicircular or other shaped seats to receive the strands of wire to be twisted together, the recesses registering, as shown in Fig. 2. These recesses hold the 50 wires during the time of twisting the first of the coils, to be hereinafter described, and the

bars about the recesses are, by preference, made of steel. At the point D the bars are also recessed to form a seat for receiving and strongly holding the first-made twist while the second 55 is being formed. These recesses are preferably serrated, so as to more strongly take hold of the twist or coil and somewhat bite into it, as it were, to positively prevent its slipping or turning.

The letter E designates the twister, the same being also constructed of metal, preferably of steel, at the head F. The other end is provided with a suitable handle, G. The head F at one edge is slotted transversely at H, for the 65 purpose of slipping over the wire about or round which the other wire is to be twisted. The head is recessed at I by a circular incision or countersink extending partly through the transverse direction of the head, the function 70 of said countersink being to receive one end of the coil or twist as the one wire is being wound round the other, as seen in Fig. 4. The head is also further recessed at J by an incision, which extends from the countersink I to the 75 edge of the head, and in which incision J that portion of the wire which is actually being wound round the other is fitted. As seen in Fig. 4, the said incision J is curved or cut to form a seat, K, for said last-mentioned portion 80 of the wire, and also to form a shoulder, L, to prevent the possibility of said wire springing out laterally while undergoing the winding process. Thus it will be seen that if two wires are brought together and placed in the relative position shown in Fig. 5 and the holder then applied, one wire fitting each recess C, the said wires will be firmly held. Then, by slipping the slot H of the twister over the body M of the wire and the countersink I over the 85 bend N and the recess J over the portion O of the wire, and then by turning the twister over and over, using the portion M as the turning-point, the portion O will be evenly and closely wound round the portion M, as seen in Fig. 4. 90 This being accomplished, the recess D of the holder is applied to the coil thus made (see Fig. 4) and the twister applied to the remaining untwisted portion, as just described.

Having thus fully described our invention, 95 what we claim as new, and desire to secure by Letters Patent, is—

1. In a wire-manipulating tool, the combination, with the holder composed of two bars pivoted together at or near one end and provided each with three recesses, one of the recesses of each bar having serrations, and the said recesses registering with each other, as described, whereby provision is made for two wires and for holding a coil of wire.
- 5 2. In a wire-manipulating tool, a twister consisting of a bar provided at one end with a transverse open slot, with a countersink, into which said slot extends, with an incision extending into said slot, and with a shoulder formed at one side of the incision and operating substantially as described.
- 10 15 2. In a wire-manipulating tool, a holder com-

posed of two bars pivoted together at or near one end and provided each with three recesses, one of the recesses of either bar having serrations, and the said recesses registering with each other, as described, whereby provision is 20 made for two wires and for holding a coil of wire.

In testimony whereof we affix our signatures in presence of two witnesses.

J. W. LEWIS.
NEWTON J. LEWIS.
